UNITED STATES PATENT OFFICE

JOHN HARWOOD, JR., OF WALSALL, ENGLAND

POCKET WALLET

Application filed February 26, 1930, Serial No. 431,513, and in Great Britain October 31, 1929.

This invention relates to pocket wallets having a back or outer and an inner panel, the latter being attached to the former by flexible connection members in order to permit relative motion between the back or outer and the inner panels for the purpose of preventing undesirable puckering of the inner panel, and one object of this invention is to provide a generally improved wallet of this kind.

A further object of the present invention is to provide a case which may have any number of inner panels in which the inner panels can slide relatively to the backing and independently of each other so that the case will lie flat when opened, and will not bulge or pucker when folded and carrying a load of papers or notes.

Referring to the drawings:—

20 Figure 1 is a perspective view of one form of pocket wallet constructed according to this invention;

Figure 2 is a similar view to Figure 1, but shows a part of the pocket wallet cut away;

25 Figure 3 is a perspective view of the same wallet as is shown in Figures 1 and 2, but is partly in section to show a detail of the pocket wallet;

Figure 4 is a horizontal cross section of 30 the pocket wallet shown in Figures 1 to 3, the wallet being shown in this view in its folded or closed position;

Figure 5 is a longitudinal cross sectional elevation of a slightly modified and opened 35 pocket wallet;

Figure 6 is a perspective view of a further modified construction of pocket wallet according to this invention, a part of the pocket wallet being cut away to illustrate 40 details;

Figure 7 is a perspective view of a further slight modification, and

45 Figures 8 and 9 are both part sectional plans of further modified methods of attaching the connection members to the wallet and the movable panels.

In carrying my invention into effect in the manner illustrated in Figures 1 to 4 of the drawings, the wallet comprises a back panel 50 1 of leather or other similar material, but

preferably of leather, and formed on or attached to the ends of this back panel are provided a pair of pockets 2, 3 which are superposed on the back panel and are directed inwardly towards the centre of the latter, 55 and have their inner ends 4, 5 open and facing one another.

Each of the pockets 2, 3 may be formed by a piece of leather doubled upon itself along a horizontal line and sewn by its vertical end 60 and its lower edge to the back panel.

Two inner panels marked 6 and 7 respectively are shown, and these panels form compartments 8 and 9 for treasury notes, or the like, and one of these compartments is formed 65 by the inner panel 6 and the back panel 1 of the wallet, whilst the other compartment is formed between the inner panels 6 and 7.

The panels 6 and 7 are both shorter than the back panel 1, and the panel 7 is shorter 70 than the panel 6. Also the panels 6 and 7 are rather narrower than the panel 1, and conveniently the panel 7 is narrower than the panel 6.

The panel 6 is connected to the back panel 1 75 by connection members 10 arranged one at each end of the panel.

The panel 7 has its ends located in the pockets 2 and 3, and these ends of the panel are connected to the insides of the pockets 2 80 and 3 by connection members 11, one of which is arranged at each end of the panel 7.

The pocket wallet is formed of fairly stout material, whilst the connection members 10 and 11 are made of very flexible material. 85 Any suitable material may be used for the connection members, but conveniently these are formed by skivers; by "skivers" I mean shavings of tough leather.

In the drawings the skivers are shown as 90 being made separately of the panels. When this is the case, each connection member or skiver has one end sewn to the wallet and the other end sewn to the panel to which it belongs.

95 There are a number of ways in which the skivers can be arranged for connecting the panels to the wallet. The method shown in Figures 1 to 4 is one in which the skivers or connection members for the panel 6 each 100

have one end sewn or otherwise connected at or near one end of the back panel, whilst the other end is doubled over and then connected to the back of the panel 6.

Similarly, each connection member 11 for the front panel 7 has one end connected to the corresponding end of the panel 7, whilst its other end is doubled upon itself and then connected to the back of one of the pockets 2, 3, according to which end of the panel 6 the connection member is attached.

By doubling the connection members upon themselves in the manner described, when the wallet is folded intermediate its ends into a position somewhat as shown in Figure 4, the ends of the panels 6 and 7 slide in the wallet and the connection members 10 and 11 have what might be termed a rolling action, as will be readily understood from consideration of the drawings.

In the arrangement shown in Figure 5, the connection members 10 and 11 are attached to the wallet and the panels 6 and 7 in rather a different manner to that previously described, the opposite ends of each of the connection members being secured to the panels and the wallet, but in this case the connection is substantially straight (that is the connections form a continuation of the panels), the skivers or connection members not being doubled upon themselves.

Thus, in this construction the distance between the points of attachment of the ends of the skivers or connection members to the wallet is greater than the distance between the attachments of the opposite ends of the connections or skivers to the inner panels.

In the modification shown in Figure 6, the skivers or connection members are similarly arranged to those shown in Figures 1 to 3, except that they are doubled upon themselves in an opposite direction to those shown in the figures referred to, and in the case of the connection members 10, one end of each is connected to the adjacent end of the panel 6, whilst the other end is folded so as to project towards the centre of the wallet and is connected to the back of one of the pockets 2, 3, instead of being connected directly to the back panel 1 of the wallet.

Figure 7 shows one of the inner panels 6 and 7 and illustrates how the ends of these panels may be skived at 16 to form flexible connection members which are integral with the panel, these connection members thus replacing the connection members 10 and 11 previously described.

Figure 8 shows a still further method of attaching the inner panels to the wallet, and in this case the connection member 10 or 11, as the case may be, has its ends doubled upon itself so that it is of approximately S formation as seen in cross sectional plan, the ends of the connection member being sewn or otherwise secured to the panel and the wallet.

In the modification shown in Figure 9, the connection member 10 or 11, as the case may be, has both of its ends doubled back upon its main part so that the ends project inwardly towards each other, and these ends are connected respectively to the inner panel and the wallet.

The connection members 10 and 11 may each be rather longer than the shortest distance between the parts of its connection to the panels so that a comparatively thick wad of notes or papers can be inserted in the wallet.

In a wallet according to any of the construction described, provision is made for permitting each inner panel to float or slide freely and independently of the other inner panels so that the case or wallet will fold flat even when fully loaded.

When the wallet is loaded and folded, the two inner panels 6 and 7 float freely in relation to the back panel 1 and in relation to each other, and the capacity of the wallet is only limited by the distance between the inner ends of the pockets 2 and 3 provided on the back panel 1, the inner ends of these pockets moving towards each other over the inner panel 7 when the wallet is folded.

In addition to the pockets 2, 3, the pocket wallet may be provided with pockets 12 and 13 formed respectively on the pockets 2 and 3, and a removable casing 14 for visiting cards may be mounted in the pocket 12, and a similar but smaller casing 15 for stamps or the like may be mounted in the pocket 13.

The present invention is equally applicable to cases which have a single fold across the middle, or to cases which have two or more folds.

It is to be understood that it is not essential for the backing panel to be provided with the inwardly extending pockets, as the ends of the inner panel or panels can be attached by skivers either directly to the backing panel, or one may be attached to the backing panel, while the other may be attached to the adjacent inner panel.

Further, it is not essential that both ends of the inner panel or panels be provided with skivers as sufficient relative motion may be obtained by providing a skiver portion at one end only.

What I claim then is:—

1. A pocket wallet comprising a back panel, an inner panel, and connection strips connected at opposite ends to the back panel, and the ends of the inner panel respectively, and formed of material relatively thinner than the said inner panel and each doubled upon itself between its ends.

2. A pocket wallet comprising a back panel, an inner panel and connection strips connected at opposite ends to the back panel and the ends of the inner panel respectively and formed of material relatively thinner than

the said inner panel and each doubled upon itself between its ends so as normally to be of flattened S form in cross section or edge elevation.

- 5 3. A pocket wallet comprising a back panel, a pair of pockets connected one to each of the opposite ends of the back panel and extending inwardly towards one another and having their open mouths at their inner ends, an
- 10 inner panel having an end projecting into each of said pockets and extending between the pockets, and connection strips each connected at opposite ends to an inner part of said pocket and an end of the inner panel
- 15 and said connection strips being formed of a material relatively thinner than the inner panel and each being doubled upon itself between its ends.
- 20 4. A pocket wallet comprising a back panel, and an inner panel formed of leather and having its integral ends skived or reduced in thickness to produce connection portions by which the inner panel is connected at its ends to the wallet, and the said skived or reduced
- 25 integral ends being doubled upon themselves between their ends.

In witness whereof I affix my signature.
JOHN HARWOOD, JR.
